UNITED STATES PATENT OFFICE.

WILLIAM M. VENABLE, OF PITTSBURGH, PENNSYLVANIA, ASSIGNOR TO BLAW-KNOX COMPANY, A CORPORATION OF NEW JERSEY.

FORM.

Application filed May 24, 1922. Serial No. 563,318.

To all whom it may concern:

Be it known that I, WILLIAM MAYO VENABLE, a citizen of the United States, residing at Pittsburgh, in the county of Allegheny and State of Pennsylvania, have invented certain new and useful Improvements in Forms, of which the following is a specification.

This invention relates to forms for use in the construction of tunnels, culverts, and the like. It is an important object of the invention that one length of the form may be collapsed and shifted along through similar lengths already set up in working position,—so that as the tunnelling advances, lengths on which the concrete tunnel lining has already hardened may be carried forward through lengths on which the lining is not yet hard, and used to mold the lining further ahead. Other objects and advantages will appear from the description, hereinafter, of the best embodiment of the invention at present known.

In the drawings, Fig. 1 shows a cross-section through the tunnel site, and affords an end view of a form length set up in working position ready for the molding of tunnel lining about it, and also of a traveller for shifting and placing the form lengths.

Fig. 2 shows a longitudinal mid-section through the parts and mechanisms illustrated in Fig. 1.

The form shown comprises, for each length, a curved top section A and a couple of partly curved side sections B so mounted and attached to the section A, at its lateral extremities, that they may be swung inward toward the center of the tunnel to collapse the form for transfer,—in the manner indicated in dotted lines in Fig. 1. As shown, the sections A, B are stiffened laterally by curved channel frames or ribs 5 and 6, which are connected and spaced apart by fore and aft members. The exterior walls of the form are completed by appropriately curved plates attached to the channels 5, 6, and are stiffened with fore and aft angle bars 7. The top form section A is braced transversely by cross braces C, interconnecting

the lateral extremities of the section. As shown, each cross brace C comprises a horizontal channel member 8,—located substantially below the top section A, but substantially above the diameter of the form 55 curve,—and a couple of upright channel members 9 connecting it to the channel rib 5, and braced thereto by suitable gusset plates 10. The fore and aft angle bar members 11 for the top section A are secured 60 to the channel members 8 and 9 of its cross brace C. The hinges 12 by which the top and side sections A and B are pivoted together are attached to the channel ribs 5 and 6. Outward movement of the side sections B in setting up the form is limited by stop means here shown as comprising bracket plates 14 attached to the ribs 6 65 and having curved slots (concentric with the hinges 12) in which are engaged bolts 70 or pins 16 in the ends of the horizontal members 8. To expand or collapse the form the side sections B may be moved outward or inward by means of expandable and collapsible lateral bracing means D, of turn-buckle construction, connected between said side sections and the lower ends of the uprights 9. In the surface plates or panels of the form, between the ribs 5, 6, are hinged doors 17 through which concrete 80 may be placed around the form from the working platform E resting on the cross braces C. As shown, there is ample headroom for working between the platform E and the form top or roof. 85

For conveying and setting up the form lengths, there may be employed a traveller here shown as comprising a main frame structure F mounted on wheels 21, and also an elevator framework G raisable above the 90 rest of the traveller. As shown, the rectangular frames F and G are of quite similar construction, and are each suitably braced and rendered rigid by diagonals 22 and gussets 23. The upright channels and plates 95 24, 25 which form the corners of the frame F are arranged to form angular guideways for the frame G, whose corners consist of upright angle bars 26. For raising and lowering the elevator G, chain block tackles

27 may be mounted at the four corners of the frame F, on its uppermost cross-members 28, and the chain ends may be attached to the horizontal members 29 of the 5 elevator G. As shown, the uppermost longitudinal members 30 of the elevator G are extended fore and aft, so as to afford bearing for all the cross braces C of each form length. The centers of the frames F and 10 G are conveniently open and clear, both fore and aft and vertically.

When the form is set up in working position, as shown in full lines, the sides B are spread apart so as to rest on shoring or 15 timbering H at the sides of the tunnel, and the whole form is firmly and rigidly braced, transversely, by the cross-braces C and the turnbuckles D, quite independently of the traveller and its elevator. Under this condition, the form may be lifted and supported independently of the traveller, on 20 the timbering H, by means of wedges 31 interposed between the timbering and the lower edge of the form sides B. When the 25 form is to be collapsed and transferred, the elevator G may be raised to engage the braces C and lift the weight of the form off the timbering H. Thereupon the wedges 31 may be knocked out, and the form sides 30 B thus released so that they can be swung inward toward the traveller and the center of the tunnel, clear of the timbering H vertically. Thus collapsed, the form may 35 be lowered by means of the elevator G until it occupies substantially the position indicated in dotted lines in Fig. 1. Under this condition, it will be seen, there is ample space and clearance for movement of a form length collapsed and lowered on the traveller beneath form lengths set up in place.

I claim:

1. A tunnel form comprising a curved top section, with a cross-brace therefor substantially above a diameter of the form curve; 45 and side sections hinged to said top section; said form when in position permitting passage therethrough past its said cross-brace of another similar form collapsed.

2. A tunnel form comprising a curved top section, with a cross brace interconnecting and bracing its lateral extremities substantially above a diameter of the form curve; curved side sections hinged to said top section; and means interconnected between top 55 and side sections for expanding or collapsing the latter; said form when in position permitting passage therethrough of another similar form collapsed.

3. A tunnel form comprising a curved top section, with a cross-brace therefor substantially therebelow and above a diameter of the form curve; and side sections hinged to 60 said top section above the horizontal member of said cross-brace; said form when in position permitting passage therethrough

past its said cross-brace of another similar form collapsed.

4. A collapsible self-supporting tunnel form comprising a substantially rigid curved top section having a cross-brace substantially therebelow and above a diameter of the form curve; curved side sections hinged to said top section above the horizontal member of said cross-brace; and expandable and collapsible lateral bracing means 70 connected between said cross-brace and said side sections, for moving the latter outward and inward; said form when in position permitting passage therethrough past its said cross-brace of another similar form collapsed. 75

5. A tunnel form comprising a curved top section with working doors therein, and a cross-brace interconnecting the lateral extremities of said section, with headroom for 80 working between them, substantially above a diameter of the form curve; and curved side sections hinged to said top section above the horizontal member of said cross brace; said form when in position permitting passage therethrough of another similar form collapsed. 85

6. Tunnel form apparatus comprising a traveller with a form-supporting elevator structure raisable above the rest of the 90 traveller; and a plurality of tunnel forms adapted to be moved along on said traveller and raised by its elevator into working position; the individual form comprising a top section, side sections hinged thereto for swinging inward from working position, and means interconnected between top and side sections for expanding or collapsing the latter, said form being capable, when lowered by the traveller elevator and collapsed as set forth, of being conveyed by the traveller through other similar forms set up in working position. 100

7. Tunnel form apparatus comprising a traveller with a form-supporting elevator structure raisable above the rest of the 11 traveller; and a plurality of tunnel forms adapted to be moved along on said traveller and raised by its elevator into working position; the individual form comprising a top 110 section, a cross-brace therefor substantially therebelow, and curved side sections hinged to said top section for swinging inward from working position, said form being capable, when lowered by the traveller elevator and collapsed as set forth, of being conveyed by the traveller through other similar forms set up in working position. 120

8. Tunnel form apparatus comprising a traveller with a form-supporting elevator structure raisable above the rest of the traveller; and a plurality of tunnel forms adapted to be moved along on said traveller and raised by its elevator into working position; the individual form comprising a top 130

section, a cross-brace interconnecting the lateral extremities of said section, and curved side sections hinged to said top section above the horizontal member of said cross-brace for swinging inward from working position, and the form being capable, when lowered by the traveller elevator and

collapsed as set forth, of being conveyed by the traveller through other similar forms set up in working position.

10

In testimony whereof, I have hereunto signed my name.

WILLIAM M. VENABLE.
